US00D860948S

(12) **United States Design Patent** (10) **Patent No.:** **US D860,948 S**
Wang (45) **Date of Patent:** **** Sep. 24, 2019**

(54) **ADAPTER**

(71) Applicant: **Guangdong Global Egrow (Zhaoqing) Cross-Border E-Commerce Co., Ltd.,**
Guangdong (CN)

(72) Inventor: **Hao Wang**, Heilongjiang (CN)

(73) Assignee: **Guangdong Global Egrow (Zhaoqing) Cross-Border E-Commerce Co., Ltd.,**
Guangdong (CN)

(**) Term: **15 Years**

(21) Appl. No.: **29/655,229**

(22) Filed: **Jul. 1, 2018**

(51) LOC (12) Cl. **13-03**

(52) U.S. Cl.

USPC **D13/137.2**

(57) **CLAIM**

The ornamental design for an adapter, as shown and described.

DESCRIPTION

FIG. 1 is a perspective view of an adapter showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings are for the purpose of illustrating portions of the adapter that form no part of the claimed design.

1 Claim, 7 Drawing Sheets
